US00D872578S

(12) **United States Design Patent** (10) **Patent No.:** **US D872,578 S**
(45) **Date of Patent:** **** Jan. 14, 2020**

(54) **PACKAGING**

(71) Applicant: **Apple Inc.**, Cupertino, CA (US)

(72) Inventors: **Alissa Anderson**, San Francisco, CA (US); **Jonathan Berk**, Mountain View, CA (US); **Margaret Madigan Burke**, Sunnyvale, CA (US); **Jack Wandlerman**, San Francisco, CA (US); **Kevin Scott Fetterman**, Los Altos, CA (US)

(73) Assignee: **Apple Inc.**, Cupertino, CA (US)

(**) Term: **15 Years**

(21) Appl. No.: **29/697,459**

(22) Filed: **Jul. 9, 2019**

Related U.S. Application Data

(63) Continuation of application No. 29/668,073, filed on Oct. 26, 2018, now Pat. No. Des. 856,147, which is a (Continued)

(74) *Attorney, Agent, or Firm* — Sterne, Kessler, Goldstein & Fox P.L.L.C.

(57) **CLAIM**

The ornamental design for packaging, as shown and described.

DESCRIPTION

FIG. 1 is a top front perspective view of packaging showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective reference view thereof showing the claimed design in an environment in which it may be used;

FIG. 9 is a top front perspective view of another packaging showing the claimed design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a top front perspective reference view thereof showing the claimed design in an environment in which it may be used.

The dashed broken lines in the figures show portions of the packaging and environment that form no part of the claimed design.

The dot-dash broken lines in the figures show boundaries that form no part of the claimed design.

1 Claim, 10 Drawing Sheets

Related U.S. Application Data

continuation of application No. 29/593,124, filed on Feb. 6, 2017, now Pat. No. Des. 832,103, which is a continuation of application No. 29/519,811, filed on Mar. 9, 2015, now Pat. No. Des. 778,161.
